DEFENSIVE PUBLICATION

UNITED STATES PATENT OFFICE

Published at the request of the applicant or owner in accordance with the Notice of Dec. 16, 1969, 869 O.G. 687. The abstracts of Defensive Publication applications are identified by distinctly numbered series and are arranged chronologically. The heading of each abstract indicates the number of pages of specification, including claims and sheets of drawings contained in the application as originally filed. The files of these applications are available to the public for inspection and reproduction may be purchased for 30 cents a sheet.

Defensive Publication applications have not been examined as to the merits of alleged invention. The Patent Office makes no assertion as to the novelty of the disclosed subject matter.

ON LINE SEQUENTIAL ESTIMATION
OF TRAFFIC FLOW DENSITY

This is a method for automatically estimating the number of vehicles present on a section of roadway from measurements of speed and vehicle flow at the entrance and exit points of the roadway section. The method comprises the steps of computing rough count estimates of the number of vehicles in said roadway at regular intervals, referred to as observation periods, and then correcting these estimates by a sequential correction scheme which filters out random errors present in the count.

At both the entrance and exit points of the roadway, detector mechanisms monitor the number of passing vehicles and their respective velocities. For each observation period, the input and output velocities are averaged and an estimate of travel time over the roadway is computed. Then, a rough estimate of the number of vehicles in the roadway is computed from an inventory of vehicle arrivals at the input of said roadway and the travel time of exiting vehicles. The rough estimate is then adjusted by means of sequential estimator which utilizes the requirement that the count obtained at the end of two successive observation periods is equal to the number of cars present in the roadway at the prior observation period plus the difference between the number of vehicles entering and exiting the roadway during the present observation.
